BEER BARREL BUNG

Samuel Gabel, Brooklyn, and David A. Fenichell,
Garnerville, N. Y.

Application December 26, 1933, Serial No. 704,042

4 Claims. (Cl. 217—111)

This invention relates to a bung especially intended for use on beer barrels and has for an object to provide an improved bung which will have all the strength of the normal bung and 5 yet at the same time will minimize the danger of the annulus of the bung from being split when the spigot is driven through the bung into the barrel.

A further object of this invention is to provide a beer barrel bung wherein the stopper portion is separated from the annulus portion by a reinforcing shoulder, thereby confining the break between the stopper portion and the annulus portion to the section below the shoulder 15 and the stopper and preventing the possibility of the annulus splitting and thus avoiding the spilling of the contents of the barrel through leakage.

Still a further object of this invention is to 20 provide a beer bung which is an improvement over the bung disclosed in the pending application, Ser. No. 689,626, filed September 15, 1933, and Ser. No. 695,670, filed October 28th, 1933 by the same inventors.

With the foregoing and other objects in view, as will hereinafter become apparent, this invention comprises the constructions, combinations and arrangements of parts, hereinafter set forth, disclosed and shown on the accompanying drawing. In this drawing,

Figure 1 is a side elevation of the lower portion of a beer barrel, partly broken away to show the new bung applied therein,

Figure 2 is a front elevation of the invention, 35 Figure 3 is a sectional view taken on the line 3—3 of Figure 2, and

Figure 4 is a sectional view through the bung showing the breaking point therein.

There is shown at 10 a fragmentary portion 40 of the beer barrel having a bung hole 11 closed by the bung 12 through which the spigot 13 is to be driven. The bung 12 includes the annulus portion 14 which fits within the bung hole 11 and the stopper portion 15, which closes the 45 opening through the annulus portion 14. One great defect of beer bungs as conventionally made, is that the spigot 13 when driven through the bung 12 is very apt to split the annulus portion 14 as it knocks the stopper portion 15 away 50 therefrom, this being true in the conventional bung where the annulus portion 14 extends in a straight line to the stopper portion 15. This is very undesirable for obvious reasons in that it allows the contents of the barrel to escape 55 through the slit and further allows the gas pres-

sure within the contents to be reduced, due to the escape through the split annulus.

The purpose of this improvement is to eliminate this undesirable feature. In this invention the annulus portion 14 does not extend straight 60 through the stopper portion 15, but instead is separated therefrom by a shoulder portion 17. As a result of the presence of this shoulder portion 17, which has an opening therethrough of sufficient diameter to allow the end of the spigot 13 65 to contact against the stopper portion 15, the strain exerted by the spigot 13 breaking away the stopper portion 15 from the annulus portion 14 is prevented from reaching the annulus portion 14 but instead is absorbed in the shoulder portion 70 17. The shoulder portion 17 thus acts to greatly reinforce the annulus portion 14 and prevents any split developing in the annulus portion 14.

In operation, this bung 12 is inserted in the 75 barrel 10 in the conventional manner and when the spigot 13 is being forced into the barrel 10 it is likewise done in the conventional manner by driving the end of the spigot 13 against the stopper portion 15, breaking the stopper portion 15 80 away from the annulus portion 14 and from the reinforcing shoulder 17. The presence of the reinforcing shoulder 17 insures a clean break and prevents any split of the annulus portion 14.

The novel features and the operation of this 85 device will be apparent from the foregoing description. While the device has been shown and the structure described in detail, it is obvious that this is not to be considered limited to the exact form disclosed, and that changes may be made 90 therein within the scope of what is claimed without departing from the spirit of the invention.

Having thus set forth and disclosed the nature 95 of this invention, what is claimed is:

1. A bung of frangible material comprising an annulus portion, a stopper portion, said annulus portion having an aperture leading to said stopper portion, and a shoulder portion connecting said annulus portion and said stopper portion whereby said stopper portion may be broken away 100 leaving said shoulder and annulus portion intact.

2. A bung of frangible material comprising an annulus portion, a stopper portion, said annulus portion having an aperture leading to said stopper portion, and a shoulder portion connecting said annulus portion and said stopper portion, said shoulder portion serving to strengthen and reinforce said annulus portion adjacent said stopper portion whereby said stopper portion may be 110

broken away leaving said shoulder and annulus portion intact.

3. A bung of frangible material comprising an annulus portion, a stopper portion, said annulus portion having an aperture leading to said stopper portion, and a shoulder portion connecting said annulus portion and said stopper portion, said shoulder portion serving to strengthen and reinforce said annulus portion adjacent said stopper portion, said shoulder portion having an aperture connecting the aperture in said annulus portion to said stopper portion whereby said stopper portion may be broken away leaving said shoulder and annulus portion intact.

15

80 85

4. A beer barrel bung of frangible material comprising an annulus portion, a straight outside wall on said annulus portion, an aperture through said annulus portion, a stopper portion closing said annulus portion, and a stepped inside wall on said annulus portion leading to said stopper portion, said stepped inside wall providing a reinforcing shoulder adjacent said stopper portion whereby said stopper portion may be broken away leaving said shoulder and annulus portion intact.
